UNITED STATES PATENT OFFICE

GEORGE KLUG, OF HAMBURG, GERMANY.

IMPROVEMENT IN VALVE-MOTIONS FOR STEAM-ENGINES.

Specification forming part of Letters Patent No. **180,040**, dated July 18, 1876; application filed April 11, 1876.

To all whom it may concern:

Be it known that I, GEORGE KLUG, of the city of Hamburg, Germany, engineer, have invented a new and useful Improvement in Valve-Motions and Reversing-Gear for Steam-Engines; and I do hereby declare that the following is a full, clear, and exact description of the same, reference being had to the accompanying drawing, which forms part of this specification, and which represents my improved valve-motion and reversing-gear applied to the slide-valve of a steam engine, and showing the same in various positions.

In said drawing, m signifies center of crank-shaft. e signifies eccentric. ll signify a guiding apparatus, movable on a certain point in a circular direction. o signifies fulcrum or point on which the guiding apparatus turns. xx signify angles, showing direction of turning guide ll on point o . efc signify eccentric-rod. mo signify direction of eccentric-rod and guide ll in their middle position. ci signify connecting-rod for the steam-valve of the cylinder. ik signify middle position of the same rod. uu vv signify lines showing outer and inner lap of valve. α signifies angle of inclination between ik and center line of cylinder.

I only use one eccentric, e , with my motion and reversing-gear, the rod of which, efc , is connected by its end e with the valve-rod ci . When the engine is in motion, the eccentric-rod receives in a point, f , of its middle part a motion in a certain line, ll , the direction of which can be altered. This motion of the point f of the eccentric-rod is caused by means of a joint-piece, which has a rotating motion with the fulcrum f , and at the same time is guided along line ll , in the direction of which the guiding apparatus is capable of being moved on point o . If the guide ll is in its mean position, mo , the engine stops; but a rotation of the guide ll , say equal to the angles xx , will cause a forward or backward motion of the engine. The guiding-line ll of the guiding apparatus is curved circular in the plane of the angles xx ; but, according to the corresponding radius of curvation, this curve may be a sharp one, and, if a slight

curve, of no practical value. The guide ll , working upon a point, f , of the middle part of the eccentric-rod, in connection with its shape, produces my new valve-motion in the point c of the eccentric and valve-rod in the direction of the center line ik of the valve-rod. This valve-motion may be altered in stroke or direction by transmissions placed between c and inner valve-rod.

The relation between the different dimensions of eccentricity em , eccentric-rod efc , radius of curvations and angles xx of guide ll gives the means of effecting an excellent distribution of steam for the corresponding engine. Therefore, the radius of curvation of the guiding-line ll depends upon the construction of the engine, and chiefly upon the relative dimensions of connecting-rod and crank.

For horizontal engines, with long connecting-rods, for example, the guiding-line can be made straight, and on the contrary for vertical engines, as used in screw-ships, the guiding-line may be made of a sharp curvation.

The position of the eccentric e on the shaft is shown in the drawing. It depends alone on the position of the fulcrum o relative to the shaft m , and is fully out of connection with the lead, expansion, or compression. The position of eccentric is such that, supposed a correct length of eccentric-rod in ef , if the crank is at the dead-points, the guided point f of the eccentric-rod falls within the axis o of guide ll .

What I claim as my invention is—

The combination of the eccentric or crank-pin and its rod efc , the angularly-adjustable guide or lever ll , along which and to opposite sides of its fulcrum o the eccentric-rod at its center f is free to slide, and the valve-rod ci , all arranged for operation in relation with the crank-shaft of the engine, substantially as shown and described, and for the purposes herein set forth.

GEORGE KLUG.
